FOLDABLE BICYCLE

Emilio Elia, Milan, Italy

Filed May 19, 1966, Ser. No. 2,485

Claims priority, application Italy Oct. 13, 1964

Term of patent 14 years

(Cl. D90—8)

Fig.3

FIGURE 1 is a front perspective view of the foldable bicycle;

FIGURE 2 is a rear perspective view of the foldable bicycle;

FIGURE 3 is a side elevational view.

This application is a continuation-in-part of application Serial No. 84,717 filed April 12, 1965 and now abandoned.

I claim:

The ornamental design for a foldable bicycle, as shown.
